CORPORATION OF NEVADA

DESIGN FOR A BADGE

Application filed August 5, 1929. Serial No. 32,309. Term of patent 14 years.

To all whom it may concern:

Be it known that we, JOHN C. TYLER and THOMAS E. LEAVEY, citizens of the United States, residing at Los Angeles, in the County of Los Angeles and State of California, have invented a certain new, original, and ornamental Design for a Badge, of which the following is a specification, reference being had to the accompanying drawing forming a part thereof in which Figure 1 is a front elevational view of the badge, and Fig. 2 is a sectional view thereof taken through 2—2 of Fig. 1.

The vertical section lining in the drawing represents the color red and the horizontal sectional lining the color blue.

We claim:

The ornamental design for a badge, substantially as shown, and described.

In testimony whereof, we have hereunto set our hands at Los Angeles, California, this 10th day of July, 1929.

JOHN C. TYLER.
THOMAS E. LEAVEY.
